UNITED STATES PATENT OFFICE.

JOSEPH ANDERSON, OF PITTSBURG, PENNSYLVANIA.

DESIGN FOR STEMS OF GLASS ARTICLES.

SPECIFICATION forming part of Design No. 11,838, dated July 6, 1880.

Application filed June 9, 1880. Term of patent 7 years.

To all whom it may concern:

Be it known that I, JOSEPH ANDERSON, of the city of Pittsburgh, in the county of Allegheny and State of Pennsylvania, have invented a new and useful Improvement in Design for Stems of Glass Articles; and I do hereby declare the following to be a full, clear, and exact description thereof, reference being had to the accompanying drawings, forming a part 10 of this specification, in which—

Figure 1 is a view of my improved design for the stems of glass articles. Fig. 2 is a view of a glass bowl provided with such a stem.

My improved design consists of a stem for 15 glass articles formed in the shape and in imitation of a horseshoe.

As illustrated by the drawings, the horseshoe-stem *a* is provided with the usual creases,

b, and nail-prints *c*. The ends rest upon and are united with the foot *d*, and the bowl *e* rests upon and is united with the front or toe part 20 of the shoe.

The design presents a handsome appearance, and satisfies a prevailing taste for designs of 25 glass articles.

What I claim as my improved design, and desire to secure by Letters Patent, is—

A stemmed article of glassware having a horseshoe-stem, substantially as described.

In testimony whereof I have hereunto set my hand.

JOS. ANDERSON.
